THERMOSTAT

Herbert J. Taylor and Gordon R. Boyd, Aloha, Oreg.,
assignors to Sunne Controls Division of Peco Manufacturing Co., Inc., Portland, Oreg.

Filed Jan. 2, 1974, Ser. No. 429,595

Term of patent 14 years

Int. Cl. D10—04

U.S. Cl. D10—50

FIG. 1

FIG. 3

FIG. 2

FIG. 4

FIG. 6

FIG. 5

FIG. 1 is a front elevational view of a thermostat showing our new design;

FIG. 2 is a right side elevational view thereof, the left side being substantially a mirror image thereto;

FIG. 3 is a rear elevational view thereof;

FIG. 4 is a bottom plan view thereof, the top plan being substantially a mirror image thereto;

FIG. 5 is a rear elevational view of another embodiment of our new design of FIG. 1 wherein a double line break switch is substituted for a single line break switch; and

FIG. 6 is a bottom plan view of FIG. 5, the top plan being substantially a mirror image thereto.

We claim:

The ornamental design for a thermostat, as shown and described.
